UNITED STATES PATENT OFFICE.

DEWEY FRANKLIN FRISTOE, OF CHAMPAIGN, ILLINOIS.

POLISHING MACHINE.

Application filed September 14, 1926. Serial No. 135,412.

This invention comprehends the provision of a polishing machine, which is simple in construction and convenient to handle and manipulate, being primarily intended for 5 polishing nickel-plated radiators and bumpers of an automobile, the invention residing in the construction, combination and arrangement of parts as claimed.

In the drawing forming part of this application like numerals of reference indicate 10 similar parts in the several views and wherein:

Figure 1 is a view in elevation.

Figure 2 is a sectional view on line 2—2 of 15 Figure 1.

Figure 3 is a fragmentary sectional view showing one of the polishing tools associated with its respective shaft.

Figure 4 is a longitudinal sectional view 20 through the polishing tool.

Referring to the drawing in detail 10 indicates an electric motor, the casing of which is equipped with a handle 11 by means of which the machine or device can be conveniently handled for the purpose intended. The 25 motor includes a shaft 12 which is provided with gears 13 adjacent the ends thereof, and these gears mesh with similar gears 14 carried by shafts 15 arranged at either side of the 30 motor shaft 12. The shafts 15 are journaled and housed in a suitable casing 16 arranged at one end of the motor casing, and may if desired be welded to the latter. The casing 16 may be formed in two sections and one of the 35 sections includes four parallel transversely extending elements such as 8 provided with bearings 9 shown as projecting elements in Figure 1, assumed to be apertured for the journals of the shafts (said projecting elements constituting bearings being illustrated in section). The switch for the motor is arranged within a handle 11 and indicated at 40 17. It will be noted upon inspection of Figure 3 that each shaft 15 is provided with an extension 18 which terminates to provide a 45 sleeve-like portion 19 threaded onto the adja-

cent end of the main section 15. The sections 18 can vary in length and be quickly attached to or removed from the main section of the shaft as will be readily understood. Each 50 shaft section 18 is adapted to have detachably associated therewith a polishing tool 20 of any desired construction, which tool is provided with a longitudinal bore 21 to receive the section 18 of the shaft, with which it is 55 held associated by a slot and pin connection. The pin 22 projects from the section 18 of the shaft, while the bore of the tool is provided with a bayonet slot 23 to accommodate the pin. It will be further noted that the section 18 of either shaft can be detached from the main section thereof, so that only one polishing tool may be used at a time, or more than 60 one tool used at the same time if desired.

While it is believed that from the foregoing 65 description, the nature and advantages of the invention will be readily apparent, I desire to have it understood, that I do not limit myself to what is herein shown and described and that such changes may be resorted to when desired as fall within the scope of what is 70 claimed.

What is claimed is:

A machine of the character described comprising an electric motor including a shaft, 75 driven shafts arranged at either side of the motor shaft and geared thereto, a frame including transverse elements in two parallel series, providing bearings for the shafts, and the gearing including two series of gear 80 wheels positioned in operative relation by the transverse elements of the frame, each driven shaft including an extension removably associated therewith, a polishing tool for each driven shaft, and having a longitudinal bore 85 for the reception of said extension, a slot and pin connection between the tool and said extension, whereby the tool can be detached therefrom, and a handle for the machine.

In testimony whereof I affix my signature.

DEWEY FRANKLIN FRISTOE.
